A. F. BREITENSTEIN

SELF OPENING DIE HEAD

Filed Sept. 16, 1926

Inventor
Albert F. Breitenstein
Signorone Earle Nichols

UNITED STATES PATENT OFFICE.

ALBERT F. BREITENSTEIN, OF NEW HAVEN, CONNECTICUT, ASSIGNOR TO THE GEOMETRIC TOOL COMPANY, OF NEW HAVEN, CONNECTICUT, A CORPORATION.

SELF-OPENING DIE HEAD.

Application filed September 16, 1926. Serial No. 135,754.

My invention relates to an improvement in self-opening die-heads of the class employing a tripping-sleeve axially movable upon an axially-movable operating-sleeve, by which latter the radially-movable chasers are forced inwardly into their cutting positions, the object being to produce a durable, reliable, and efficient die-head constructed with particular reference to compactness as to its radius, so that a tripping-sleeve may be employed without necessitating a radius greater than that of a corresponding fixture not using a tripping-sleeve for the tripping function.

With these ends in view, my invention consists in a self-opening die-head characterized by having its body, its chaser-operating sleeve, and its tripping-sleeve respectively reduced in diameter so as to provide each with two parallel bearing-surfaces of different diameters, whereby these three main elements of the die-head are nested together for the purpose of keeping the ultimate diameter of the die-head at the minimum diameter and for the additional purpose of providing bearings of such nature as to prevent the cramping of the parts when in operation.

My invention further consists in a self-opening die-head characterized as above and having certain other details of construction and combinations of parts as will be herein-after pointed out in the claims.

In the accompanying drawings:

Fig. 1 is a view in side elevation of a self-opening die-head embodying my invention;

Fig. 2 is a view thereof in front elevation;

Fig. 3 is a view thereof in transverse section on the line 3—3 of Fig. 1;

Fig. 4 is a broken longitudinal section on the line 4—4 of Fig. 2;

Fig. 5 is a broken detail sectional view on the line 5—5 of Fig. 2;

Fig. 6 is a detached view, partly in side elevation and partly in longitudinal section, of the operating-sleeve of the die-head; and

Fig. 7 is a corresponding view of the tripping-sleeve thereof.

In carrying out my invention, as herein shown, I employ a skeleton die-body 10 hav-

ing an integral hollow shank 11 at its rear end and formed at its forward end with four radial grooves 12 receiving a corresponding number of radially-movable chasers 13, each provided with a rearwardly-projecting pin 14 engaged by a spring-actuated plunger 15 located in a radial bore 16 directly back of the groove 12 in which the chaser reciprocates. The inner ends of the said chasers are provided with the usual cutting-teeth, while their outer ends are beveled as at 17 for co-action with bevels 18 in the forward end of an operating-sleeve 19 having axial movement upon the die-body 10, and formed at its rear end with an integral annular extension 20 of smaller external diameter than the external diameter of said forward end. The interior wall of the said extension 20 has sliding bearing upon an internally-threaded adjusting-nut 21 mounted upon the externally-threaded portion of the die-body 10 and virtually forming a part thereof in the functioning of the die-head. The said adjusting-nut is formed upon its inner periphery with an annular groove 22 receiving a locking-segment 23 normally urged outward into its locking position by helical springs 24 interposed between its respective ends and the ends of a filler-segment 25 located diametrically opposite it in the said groove 22 and held against endwise displacement therein by being secured by rivets 26 to a key 27 in the sleeve 19, whereby the locking-segment is maintained in correct position with respect to the operating-sleeve 19. The springs 24 aforesaid normally urge the locking-segment 23 outward into an eccentric locking-groove 28 in the inner periphery of the extension 20 of the sleeve 19, so that the forward face of the segment engages with the forward wall 29 of the said groove 28, whereby the operating-sleeve 19 is held in its forward or chaser-closing position against the urge of two operating-springs 30 interposed between the die-body 10 and the sleeve 19 and exerting a constant effort to move the sleeve from front to rear, the forward ends of the springs being extended into sockets 31 in the said die-body 10 and their rear ends being extended into

sockets 32 in the said extension of the sleeve. For disengaging the locking-segment 23 from the shoulder 29, I employ a transmission-member in the form of a ball 33 located 5 in a radial passage 34 in the extension 20. This ball engages with the outer face of the said segment and projects into a segmental notch 35 formed in the inner periphery of an axially-movable tripping-sleeve 36, which, 10 at its rear end, is reduced in internal diameter as at 37 to correspond to the external diameter of the extension 20 upon which it axially rides. The forward end of the said tripping-sleeve has sliding bearing upon the 15 operating-sleeve 19. The reduction in the diameter of the tripping-sleeve as at 37 produces a shoulder 38 between its ends normally resting against the shoulder 39 formed 20 between the main body of the operating-sleeve 19 and extension 20 thereof. The notch 35 aforesaid is formed with an inclined forward wall 40 co-acting with the ball 33 when the tripping-sleeve is moved from front to rear with respect to the operating-sleeve, so as to crowd the ball radially inward and therefore move the segment 23 inward out of engagement with the shoulder 29 before mentioned. At its rear end 25 the tripping-sleeve is formed with an external annular groove 41 receiving a yoke or other suitable abutment installed in the ordinary manner in the machine in which the fixture is used.

It will thus be seen, and particularly by 30 reference to Fig. 4 of the drawings, that the rear ends of the operating- and tripping-sleeves are nested together by the reduction of the rear end of the operating-sleeve in external diameter and fitting the internal 35 diameter of the rear end of the tripping-sleeve to it, whereby the annular groove designed to receive the yoke or other stop-abutment may be carried so far inward toward the axial center of the die-head that 40 despite the employment of a tripping-sleeve to discharge the tripping function of the die-head, the distance from the axial center of the fixture to the external periphery of the tripping-sleeve need be no greater than 45 the distance from the axial center of the fixture to the extreme tip of the tripping-member ordinarily mounted in the operating-sleeve and projecting therefrom, such, for instance, as in United States Patent No. 55 1,563,108, dated November 24, 1925, and United States Patent No. 1,579,912, dated April 6, 1926.

As shown, a stop-member 42, located in a slot 43 in the adjusting-nut 21, provides for 60 normally checking the operating-sleeve at the limit of its chaser-retracted position. When it is desired to remove the chasers from the fixture, the stop-member is manually pressed inward to permit the operating-sleeve to move rearward into its chaser-

clearance position, but as this forms no part of my present invention, it has not been illustrated in detail.

It will be seen from the foregoing, that in a tripping-sleeve die-head constructed in accordance with my invention, the radius of its swing is kept at the minimum by nesting its three main elements, that is to say, its body, its operating-sleeve, and its tripping-sleeve, by reducing them in diameter back 70 of their forward ends so that each is provided with two parallel bearing-surfaces. In the construction shown, one of the bearings for the operating-sleeve is provided by the adjusting-nut, which, as before pointed out, virtually forms a part of the body, since it is moved with respect to the die-body only very slightly and then only occasionally to adjust the cutting diameter of the dies. 75

I claim:

1. A self-opening die-head having a body reduced in diameter back of its forward end, radially-movable chasers installed in the forward end of the said body, an axially-movable chaser-operating sleeve embracing said body and reduced in external and internal diameter back of its forward end and having bearing upon the forward end of the said body and also upon the reduced rear portion thereof, a releasable locking-member for holding the said sleeve in its chaser-closing position, and a cup-shaped tripping-sleeve embracing said operating-sleeve and having axial movement upon the said operating-sleeve for operating the said locking-member to release the same, and reduced in internal diameter back of its forward end and bearing upon the forward end of the said operating-sleeve and also upon the reduced rear portion thereof, whereby the said body and the said sleeves are nested for reducing the ultimate diameter of the fixture, the external diameter of the rear portion of said tripping-sleeve being substantially no greater than the forward portion thereof. 100

2. A self-opening die-head having a body reduced in diameter back of its forward end, radially-movable chasers installed in the forward end of the said body, an adjusting-nut mounted upon the reduced rear portion of the body, an axially-movable chaser-operating sleeve embracing said body and reduced in external and internal diameter back 105 of its forward end and having bearing upon the forward end of the said body and also upon the said adjusting-nut, a releasable locking-member for holding the said sleeve in its chaser-closing position, and a cup-shaped tripping-sleeve embracing said operating-sleeve and having axial movement upon the said operating-sleeve for operating the said locking-member to release the same, and reduced in internal diameter back of its forward end and bearing upon the forward end of the operating-sleeve and also upon the re- 110

115

duced rear portion thereof, whereby the said body and the said sleeves are nested for reducing the ultimate diameter of the fixture, the external diameter of the rear portion of said tripping-sleeve being substantially no greater than the forward portion thereof.

3. A self-opening die-head having a body reduced in diameter back of its forward end, 10 radially-movable chasers installed in the forward end of the said body, an axially-movable chaser-operating sleeve embracing said body and reduced in external and internal diameter back of its forward end and 15 having bearing upon the forward end of the said body and also upon the reduced portion thereof, a releasable locking-member for holding the said sleeve in its chaser-closing position, and a cup-shaped tripping-sleeve 20 embracing said operating-sleeve and having axial movement upon the said operating-sleeve for operating the said locking-member to release the same, and reduced in internal diameter back of its forward end 25 and bearing upon the forward end of the operating-sleeve and also upon the reduced rear portion thereof and provided with an external annular groove in line with its reduced portion, whereby the said body and 30 the said sleeves are nested for reducing the ultimate diameter of the fixture, the external diameter of the rear portion of said tripping-sleeve being substantially no greater than the forward portion thereof.
- 35 4. A self-opening die-head having a body reduced in diameter back of its forward end, radially-movable chasers installed in the forward end of the said body, an axially-movable chaser-operating sleeve embracing said body 40 and reduced in external and internal diameter back of its forward end and having bearing upon the forward end of the body and also upon the reduced rear portion thereof, a releasable locking-member for 45 holding the said sleeve in its chaser-closing position, and a cup-shaped tripping-sleeve embracing said operating-sleeve and having axial movement upon the said operating-sleeve for operating the said locking-member 50 to release the same, and reduced in internal diameter back of its forward end and bearing upon the forward end of the operating-sleeve and also upon the reduced rear portion thereof and provided with an external 55 annular groove and an internal slot, both in line with its reduced portion, and the said slot having its forward wall beveled, whereby the said body and the said sleeves are nested for reducing the ultimate diameter 60 of the fixture, the external diameter of the rear portion of said tripping-sleeve being substantially no greater than the forward portion thereof.

5. A self-opening die-head having a body 65 reduced in diameter back of its forward

end, radially-movable chasers installed in the forward end of the said body, an adjusting-nut mounted upon the reduced rear portion of the said body and provided with an annular external groove, an axially-movable 70 chaser-operating sleeve embracing said body and reduced in external and internal diameter back of its forward end and having bearing upon the forward end of the said body and also upon the said adjusting-nut 75 and formed with a radial passage, an axially-movable cup-shaped tripping-sleeve embracing said body and reduced in internal diameter back of its forward end and bearing upon the forward end of the operating-sleeve and also upon the reduced rear portion thereof and provided with an external annular groove and with an internal slot 80 having its forward wall beveled, the said groove and slot being in line with its reduced rear portion, a releasable locking-member located in the said groove of the adjusting-nut, and a transmitting-member located in the said passage of the operating-sleeve in position to transmit the movement 85 of the tripping-sleeve to the said locking-member, the external diameter of the rear portion of said tripping-sleeve being substantially no greater than the forward portion 90 thereof.

6. A self-opening die-head having a body reduced in diameter back of its forward end to provide two parallel external bearing-surfaces of different diameters; radially-movable chasers installed in the forward end of the said body; an axially-movable chaser-operating sleeve embracing said body and having chaser-closing and chaser-retracted positions, the said sleeve being reduced in internal diameter back of its forward end to provide two parallel internal bearing-surfaces of different diameters; a releasable locking-member for holding the said sleeve in its chaser-closing position; and an axially-movable cup-shaped tripping-sleeve embracing said operating-sleeve and reduced in internal diameter back of its forward end to provide two parallel internal bearing-surfaces of different diameters; said reduced portions of the body, operating-sleeve, and tripping-sleeve being nested together and prevented from cramping, the external diameter of the rear portion of said tripping-sleeve being substantially no greater than the forward portion thereof.

7. A self-opening die-head having a body reduced in diameter back of its forward end to provide two parallel external bearing-surfaces of different diameters; radially-movable chasers installed in the forward end of the said body; an axially-movable chaser-operating sleeve embracing said body and having chaser-closing and chaser-retracted positions, the said sleeve being reduced in external diameter back of its forward end 130

1 and reduced in internal diameter back of its forward end to provide two parallel internal bearing-surfaces of different diameters for bearing respectively upon the said parallel bearing-surfaces of the body; a releasable locking-member for holding the said sleeve in its chaser-retracted position; and an axially-movable cup-shaped tripping-sleeve embracing said operating sleeve and 10 reduced in internal diameter back of its forward end to provide two internal bearing-surfaces of different diameters; said reduced portions of the body, operating-sleeve, and tripping-sleeve being nested together 15 and prevented from cramping, the external diameter of the rear portion of said tripping-sleeve being substantially no greater than the forward portion thereof.

8. A self-opening die-head having a body 20 reduced in diameter back of its forward end to provide two parallel external bearing-surfaces of different diameters; radially-movable chasers installed in the forward end of the said body; an axially-movable chaser-operating sleeve embracing said body and having chaser-closing and chaser-retracted positions, the said sleeve being reduced in external diameter back of its forward end, and reduced in internal diameter back of its 25 forward end to provide two parallel internal bearing-surfaces of different diameters; a releasable locking-member for holding the said sleeve in its chaser-closing position; a cup-shaped tripping-sleeve embracing said 30 operating-sleeve and having axial movement upon the said operating-sleeve for operating the said locking-member to release the same and reduced in internal diameter back of its forward end to provide two parallel internal bearing-surfaces of different diameters; said reduced portions of the body, operating-sleeve, and tripping-sleeve being nested together and prevented from cramping, the external diameter of the rear portion of said 35 tripping-sleeve being substantially no greater than the forward portion thereof.

9. A self-opening die-head having a body 40 reduced in external diameter back of its forward end to provide two parallel bearing-surfaces of different diameters; radially-movable chasers installed in the forward end of the said body; spring means normally tending to urge the said chasers radially outward; an axially-movable chaser-operating sleeve embracing said body for moving the said chasers radially inward and having chaser-closing and chaser-retracted positions, the said sleeve being reduced in internal diameter back of its forward end to provide 45 two parallel internal bearing-surfaces of different diameters; a releasable locking-member for holding the said sleeve in its chaser-closing position; means tending to move the sleeve into its chaser-retracted position; a cup-shaped tripping-sleeve embracing said operating-sleeve and having 50 axial movement upon the said operating-

sleeve embracing said operating sleeve and reduced in internal diameter back of its forward end to provide two parallel internal bearing-surfaces of different diameters; said reduced portion of the body, operating-sleeve, and tripping-sleeve being nested together, the external diameter of the rear portion of said tripping-sleeve being substantially no greater than the forward portion thereof. 70

10. A self-opening die-head having a body reduced in diameter back of its forward end to provide two parallel external bearing-surfaces of different diameters; radially-movable chasers installed in the forward end 80 of the said body; spring means normally tending to urge the said chasers radially outward; an axially-movable chaser-operating sleeve embracing said body for moving the said chasers radially inward and having chaser-closing and chaser-retracted positions, the said sleeve being reduced in external diameter back of its forward end and reduced in internal diameter back of its forward end to provide two parallel internal bearing-surfaces of different diameters for bearing respectively upon the said parallel bearing-surfaces of the body; a releasable locking-member for holding the said sleeve in its chaser-retracted position; means tending to move the sleeve into its chaser-retracted position; and an axially-movable cup-shaped tripping-sleeve, embracing said operating sleeve and reduced in internal diameter back of its forward end to provide two parallel internal bearing-surfaces of different diameters; said reduced portions of the body, operating-sleeve, and tripping-sleeve being nested together and prevented from cramping, the external diameter of the rear portion of said tripping-sleeve being substantially no greater than the forward portion thereof. 90

11. A self-opening die-head having a body reduced in diameter back of its forward end to provide two parallel external bearing-surfaces of different diameters; radially-movable chasers installed in the forward end of the said body; spring means normally tending to urge the said chasers radially outward; an axially-movable chaser-operating sleeve embracing said body for moving the said chasers radially inward and having chaser-closing and chaser-retracted positions, the said sleeve being reduced in external diameter back of its forward end, and reduced in internal diameter back of its forward end to provide two parallel internal bearing-surfaces of different diameters; means tending to move the sleeve into its chaser-retracted position; a releasable locking-member for holding the said sleeve in its chaser-closing position; a cup-shaped tripping-sleeve embracing said operating-sleeve and having axial movement upon the said operating-sleeve. 100

115

120

sleeve for operating the said locking-member to release the same and reduced in internal diameter back of its forward end to provide two parallel internal bearing-surfaces of different diameters; said reduced portions of the body, operating sleeve, and tripping-sleeve are nested together and prevented from cramping, the external diameter of the rear portion of said tripping-sleeve being substantially no greater than the forward 10 portion thereof.

In testimony whereof, I have signed this specification.

ALBERT F. BREITENSTEIN.
